(57) **CLAIM**

The ornamental design for a water bottle, as shown and described.

DESCRIPTION

FIG. 1 is a perspective view of a first embodiment of a water bottle embodying the new design;

FIG. 2 is a left side elevational view thereof;

FIG. 3 is a right side elevational view thereof;

FIG. 4 is a top plan view thereof; and

FIG. 5 is a bottom plan view thereof;

FIG. 6 is a rear elevation thereof;

FIG. 7 is a front elevation thereof;

FIG. 8 is a perspective view of a second embodiment of a water bottle embodying the new design;

FIG. 9 is a left side elevational view thereof;

FIG. 10 is a right side elevational view thereof;

FIG. 11 is a top plan view thereof; and

FIG. 12 is a bottom plan view thereof; and,

FIG. 13 is a rear elevation thereof.

The front elevation view of the second embodiment is the same as that shown in FIG. 7.
